UNITED STATES PATENT OFFICE.

ARMAND GODEFROID, OF BERLIN, GERMANY.

ELECTRICAL CASH-CONTROLLING APPARATUS.

1,068,760.

Specification of Letters Patent. Patented July 29, 1913.

Application filed October 10, 1911. Serial No. 653,923.

To all whom it may concern:

Be it known that I, ARMAND GODEFROID, a citizen of the Empire of Germany, residing at Berlin, in the Empire of Germany, have 5 invented a new and useful Electrical Cash-Controlling Apparatus, of which the following is a specification.

My invention relates to improvements in electrical cash controlling apparatus comprising a cash transporting band, a cash receiving device and a cash registering device; and the objects of my improvement are, first, to provide a single operating device adapted to occupy three different positions, so that it can couple the receiving device and the registering device together in the middle position and either of them in either extreme position with the electromotor, and, second, to provide a rocking counting board for receiving the cash and means operated from the mechanism for turning upward the counting board, so as to drop the cash on the cash transporting band. The operating device comprises two hand-levers, which may be operated simultaneously or separately for producing certain effects to be hereinafter described.

Other improvements will be hereinafter set forth and pointed out in the claims.

I will now proceed to describe my invention with reference to the accompanying drawing, in which—

Figure 1 is a perspective view of the entire apparatus, Fig. 2 is a perspective rear view of the same on a reduced scale, Fig. 3 is a plan view of the entire apparatus, the cover being removed and parts being broken away, Fig. 4 is a vertical section on an enlarged scale through the line C—D in Fig. 3, seen in the direction of the arrows, and shows in a side view the electromotor, the driving gear and the operating device, Fig. 5 is a plan view of the same, parts being shown in section, Fig. 6 is a vertical section on an enlarged scale through the line A—B in Fig. 3, seen in the direction of the arrows, and shows the mechanism for rocking the counting board, also feeding a writing device and a counter, a part of the frame being broken away, Fig. 7 is a plan view of the same, Fig. 8 is a side view of the cash transporting band and a vertical section through a part of the drawer, Fig. 9 is a rear view of the operating device, Fig. 10 is a side view of the same, and Fig. 11 is a

vertical section similar to Fig. 4, from which the electromotor is omitted. Fig. 12 is a side view of the cash receiving and registering devices (71, 72, 73); and Fig. 13 is a plan view of the printing roll and its operative connections, the cover and the number wheel of the registering device being removed and parts being broken away.

Similar characters of reference refer to similar parts throughout the several views.

Within the casing 1 is disposed an electromotor 3, in the circuit of which is inserted a spring-contact 4 having a contact spring above provided with a thumb 5 of ebonite, saponite, or the like, on which a lever 7 rests, that loosely turns on a pin 8 and is supported by an adjustable spring 6. The contact parts 4 are fastened to a wooden block 9, the contact spring being separated from the other part by an intermediate piece 10 of insulating material. The closing of the spring-contact 4 can be effected in two manners. Either it is effected by means of a key 11, the rod 12 of which is pivotally connected with an arm 13 on a shaft 14 carrying at the other end a second arm 15, whose free end bears from above against the free end of the lever 7. The shaft 14 is mounted to rock in bearings on a frame 16 in the casing, so that on depressing the key 11 the two arms turn downward and the contact spring is pressed on the lower part 4. The free end of the lever 7 is made to normally come into contact also with a rod 19 (Figs. 9 and 10), which is longitudinally 90 movable in a guide 17, is subjected to the influence of a helical spring 18, and carries at the upper end a small roller 20. The guide 17 forms a part of a plate 21, which is fastened to a traverse 22 that is suitably secured in the casing 1. On this plate 21 is disposed a movable plate 23, which is guided by screws 24, 24 engaging in its slots 25, 25, so that the plate 23 can slide to and fro on the plate 21. The plate 23 is at its two lower corners provided with arms 26, 26, the free ends of which engage in grooves 27, 27 of clutch members 28, 28 for a purpose to be mentioned later on. On the plate 21 is further disposed a pin 31, on which two hand-levers 29, 30 are mounted to rock in such a manner, that the smaller lever 29 can engage in the space of the larger, forked lever 30 and can move through this space. The smaller hand-lever 29 is widened at its lower 110

end so as to form two opposite cams 32, 32 and is provided with a recess 32 diverging downward, in which the small roller 20 of the rod 19 normally engages. The forked hand-lever 30 carries a roller 33, which during the motion of the lever can strike either of two pins 34, 34, whereby the plate 23 is shifted on the plate 21. On one side of the guide 17 a bent lever 35 with arms of different size is mounted to rock and serves as a lock. The longer arm of this lever engages in the path of a pin 36 (Fig. 5), which is disposed on one of the driving disks of the main shaft and serves a purpose to be mentioned later on. The shorter arm of the lever 35 is at its upper free end cut out, whereby a sort of nose is formed. In the half of the movable plate 23 corresponding to the bent lever 35 several tooth spaces 37 are provided at the lower edge, while the stationary plate 21 is provided with a recess 38 corresponding to these tooth spaces. The upper end of the short arm of the lever 35 is adapted to engage in any tooth space 37 and thus to prevent the plate 23 from shifting on the plate 21.

The driving of the main shaft 42 is effected from the motor shaft by means of a worm 39 and a worm wheel 40, which is loose on the main shaft 42. The worm wheel 40 is on one side protected from shifting by a loose collar 41 with a set-screw and forms on the other side one member of a friction clutch, the other member 43 of which is fastened upon the main shaft 42. On both sides of the worm wheel and the friction clutch the said two clutch members 28, 28 are disposed on the main shaft 42 and are in any known manner prevented from turning thereon. As already mentioned, the arms 26 of the plate 23 engage in the grooves 27, 27 of these two clutch members. The latter carry pins 44, 44, which can engage in holes of the other clutch members 45, 45 that are loose on both ends of the main shaft 42 while being prevented from longitudinal motion and are made in one with pinions 46 and 47 respectively. The pinion 47 on one end of the main shaft meshes with a gear wheel 50 (not shown) of the cash receiving device to be mentioned later on. The pinion 46 on the other end of the main shaft meshes with a gear wheel 48 fastened on the shaft 49^a of the driving roll 49 for the cash transporting band 50 (Fig. 8). The ratio of the pinion 46 and the gear wheel 48 is so selected, that during every complete revolution of the main shaft 42 the shaft 49^a makes but one quarter of a revolution. The two rolls 49, 52 of the endless band 50 are mounted to turn in a frame 51 and have each in the middle a neck 53, in which teeth 54 are provided, that are adapted to engage in corresponding holes 55 of a strip 57 of leather or the like fastened to the inside of the transport band 50. The lat-

ter is on the outside provided with several cross bars covered with suitable material, whereby the transport band is divided into sections. Above the driving roll 49 is disposed the device for dropping the coins. 70 This device consists of a counting board 60, which is corrugated in the dropping direction and is mounted to rock with its shaft 59 (Fig. 6) in the frame 51. Its front edge is adapted to normally engage closely beneath the corresponding edge of a glass plate 82 covering the transport band 50. At the rear edge on the right in Fig. 3 the counting board 60 is pivotally connected with a lever 61, which is cranked, so as to engage through the frame 51 to without and to be parallel with the frame wall. This outer part of the lever 61 is forked and the fork 62 is guided by the shaft 49^a (Fig. 7) of the roll 49 engaging in its slot. Close to the fork 62 a 85 cam disk 63 (Figs. 6 and 7) having four cams is fastened on the shaft 49^a and a roller 64 mounted on the forked lever 61, 62 is made to normally engage in any space of this cam disk 63, whereby the counting board 60 is held in its normal position shown in full lines in Fig. 6. At the right end of the shaft 49^a in Fig. 7 is fastened a star wheel 65 having semicircular recesses in its four spaces. Into any of these recesses a 90 roller 66 is made to normally engage (which roller is disposed on the free end of the rear arm of a two-armed lever 67 mounted to rock at the frame of the writing or registering device of any known construction. The free end of the front arm of the lever 67 carries a pawl 68, which engages in the tooth spaces of a ratchet wheel 69 for feeding the paper strip of the above registering device, the paper strip passing from a roll 78 over the 100 table 79 under the opening 74 in Fig. 1 to another roll 80. The rear arm of the lever 67 is pivotally connected by a rod 70 with a crank 81^a on a crankshaft 81 (Fig. 7) of a known automatic registering device 75. 105 The disposition of the several registering devices can be clearly seen from Fig. 1, the cash receiving and registering device being on the left and the cash registering device on the right. The receipt forms are inserted one after the other in an upper opening 71, pass between the rolls of a printing and registering device of any known construction situated under the plate 72 and moved at every rotation by the pinion 47 while being 115 printed and registered, and issue from the lower opening 73. The amount paid in is written through an opening 74 in the cover on the paper strip mentioned above, after which this paper strip is fed one tooth forward beneath a glass plate 82 and at the same time the payment effected is automatically registered by the device 75 which is moved at every rotation by the star wheel 65 fastened on the shaft 49^a, the two levers 120 125 130

67 and 70, the crank 81^a, the crank shaft 81 and a ratchet device of any known type arranged at the outer end of the shaft 81.

The pinion 47 meshes with a gear-wheel 83 fastened on the shaft of the printing roll 84 which co-acts with a counter-roll 85 and prints the dates and the words "Payment received" onto the receipt forms. Between the gear-wheel 83 and the printing roll 84 a cam 86, is fastened on the shaft of the printing roll 84. This cam co-acts with a lever 87 adapted to be rocked once only for every complete revolution of the printing roll 84. The free end of the lever 87 is provided with a slot in which the pin of a spring-held lever 88 engages. This lever 88 is fixed on a short shaft 88^a having a spring-held pawl 89 which engages in a ratchet wheel 90 provided with ten teeth and fixed on the shaft 20 of the first number disk of the counting device 72. By means of the levers 87, 88 and of the pawl 89 the ratchet wheel makes but one tenth of a revolution during every complete revolution of the printing roll 84. In this manner the number of times that a receipt form has been inserted into the opening 71 is exactly registered, *i. e.*, how often a payment has been received.

76 is a receptacle for change coins and 77, 77 are plates corrugated in a direction opposite to the counting board 60 and serving as salvers, on which the change is placed. The corrugations of these salvers are to facilitate the removal of the coins. The drawer 2 may be made accessible to the cash-keeper or it may be kept closed, as may be preferred.

The operation of the apparatus is as follows: When any amount is to be paid in and at the same time a receipt is to be given out, then the coins are placed on the corrugated counting board 60, the amount is written down on the paper strip through the opening 74, and the two levers 29 and 30 are moved into their middle position, so that the rod 19 (Figs. 9 and 10) does not depress the lever 7. Thereupon the key 11 is depressed, so that by means of the lever 7 the upper part of the spring contact 4 is pressed on the lower part for closing the circuit of the electromotor 3 and consequently the motor is started. For the named middle position of the two hand-levers 29, 30 the movable clutch members 28, 28 occupy such a position, that their pins 44, 44 simultaneously engage in the holes of the two other clutch members 45, 45, so that the motor 3 by means of the main shaft 42 simultaneously turns the two pinions 46 and 47. In consequence of this the pinion 47 on the lower end of the main shaft 42 in Fig. 5 will drive the cash receipting device, while the other pinion 46 on the upper end of the main shaft 42 in Fig. 5 will by means of the gear wheel 48 drive the shaft 49^a for moving the coin

transporting band 50. The cam disk 63 fastened on this shaft 49^a will turn through an angle of 90° for first turning by means of the lever 61 the counting board 60 upward into the position indicated by dotted lines in Fig. 6 and thus dropping the coins during the first part of the turn, then returning the counting board into its initial position. As already mentioned above, the cam disk 63 makes but one quarter of a revolution on every complete revolution of the main shaft 42. Simultaneously with the rocking motion of the counting board 60 and the feed of the coin transporting band 50 also the registering device 75 is operated from the star wheel 65 on the shaft 49^a for registering the payment. During the turn of this star wheel 65 through an angle of 90° the lever 67 is rocked for feeding by means of the pawl 68 the paper strip forward and thus moving the last writing on it beneath the glass plate 82 and at the same time by means of the rod 70 and the crank 81^a the automatic registering device 75 is fed one figure forward.

By depressing the key 11 the armature of the electromotor is set to rotate rapidly, but this great speed is for the main shaft 42 reduced by the worm gearing 39, 40. Obviously after the encashment and feed of the coin transporting band and of the registering devices the whole mechanism will require to be stopped. For this purpose the following arrangement is made: The friction clutch member 43 disposed above the lever 7 is provided with a notch 78 (Fig. 11), in which a pin 79 provided on the lever 7 can engage. From an examination of Fig. 11 it will be evident, that on depressing the key 11 the pin 79 will withdraw from the notch 78 of the member 45 and thus permit the armature of the electromotor to rotate. During the revolution of the main shaft 42 the circumference of the member 43 will press on the pin 79 and thus keep the spring contact 4 closed, until under the action of the spring 6 the pin 79 engages in the notch 78 and strikes its radial face, whereby the friction member 43 is stopped and therewith also the whole mechanism. As the spring contact 4 is opened, no current passes through the electromotor 3, so that its armature is easily and soon stopped, the worm wheel 40 turning on the main shaft 42 and being braked by the friction clutch 40, 43.

When only the cash receipting device is to be actuated, after the payment, the two hand-levers 29, 30 are both turned from their middle position to the left in Fig. 3, that is to the right extreme position indicated by dotted lines in Fig. 9, so that the roller 33 on the hand-lever 30 striking the right pin 34 in Fig. 9 will thereby shift the plate 23 to the left in Fig. 3. The conse-

quence of this is, that by the two arms 26, 26 of the plate 23 the two clutch members 28, 28 will be equally shifted to the left in Fig. 3, so that the pins 44 of the right clutch member 28 in Fig. 3 withdraw from the holes of the corresponding other member 45, while the pins 44 of the left clutch member 28 engage more deeply into the holes of the corresponding other member 45 made in the one with the pinion 47. Of course the pins 44, 44 require to have such a length, that for the middle position of the plate 23 the pins 44, 44 of the two clutch members 28, 28 still engage in the holes of the corresponding other members 45, 45, while in either position of the plate 23 one clutch 28, 45 remains engaged, and the other clutch is disengaged. Evidently by shifting the plate 23 to the left in Fig. 3 and disengaging the right clutch 28, 45 also the spring-pressed lever 7 will be depressed by the lower cam of the hand-lever 29 depressing the roller 20 and therewith the spring-pressed rod 19, whereby the circuit of the electromotor 3 is closed. Then the cash receiving device on the left alone will be actuated in the manner as described above, while the coin transporting band 50 and the cash registering device on the right remain stopped. On releasing the small hand-lever 29 the rod 19 will under the action of the spring 18 recoil upward and return the hand-lever 29 to its middle position by reason of the special shape of the two cams 32 on the lever 29.

In consequence of this the spring-pressed lever 7 will be released by the rod 19, so that the spring-contact 4 will be opened on the pin 79 engaging in the notch 78 of the friction member 43 after the completion of one revolution of the main shaft 42. When, on the contrary, it is desired to register only the encashment without giving out any receipt, then the two hand-levers 29, 30 are turned to the right in Fig. 3 (to the left in Fig. 9), so that the left clutch 28, 45 is disengaged and the right one alone is engaged. In this case the plate 23 will be shifted to the right by the roller 33 on the hand-lever 30 striking the other pin 34 (on the left in Fig. 9), so that by the two arms 26, 26 the two clutch members 28, 28 are shifted to the right for producing the effect mentioned. At the same time the hand-lever 29 will by its other cam 32 have depressed the rod 19 by means of the roller 20 and thus closed the circuit of the electromotor 3, so that the counting board 60, the coin transporting band 50, the recording and registering devices on the right alone will be actuated in the manner described above, while the devices on the left remain stopped.

It is obvious, that the single operations, that is the receiving alone on the one hand and the encashment and registering alone on the other hand can be repeated several

times without simultaneously adjusting the two hand-levers 29, 30. It is only necessary to turn the large hand-lever 30 into the respective extreme position and to leave the small hand-lever 29 in its normal, *i. e.* middle position, whereupon by depressing the key 11 the electromotor is started for driving the respective devices. 70

In order to prevent any disengagement of the respective clutch and any stoppage of the motion before the main shaft 42 has completed its revolution, the said lock 35 is provided on the guide 17 on the plate 21. During the standstill of the machine the long arm of the lever 35 bears on the stop 36 on the friction clutch member 43 in a position indicated by dotted lines in Fig. 10, so that its short arm is kept out of reach of the edge of the plate 23 which latter therefore can be shifted at pleasure. When the main shaft 42 commences its revolution the stop 36 on the member 43 will release the long arm of the lever 35, which therefore drops, so that its short arm engages in the opposite tooth space of the plate 23 and consequently the latter is prevented from moving, until the main shaft 42 completes its revolution and its stop 36 again raises the long arm of the lever 35 and withdraws the short arm of the same from the tooth space, whereby the plate 23 is again released. In this manner it is rendered impossible to engage or disengage any of the devices during the revolution of the main shaft 42. 90

The electrical cash controlling apparatus 100 can be varied in many respects without departing from the spirit of my invention.

I claim:

1. In a cash controlling apparatus, the combination with an electromotor, of a main shaft adapted to be driven from said electromotor, a cut-out, a circuit including said electromotor and said cut-out, a cash receiving device, a cash registering device, a single operating device adapted to move 105 from one extreme position to another extreme position adapted to operate said cut-out and to simultaneously couple said main shaft with said receiving device in one extreme position and with said registering device in the other extreme position and with both of these devices in the middle position, means for permitting said main shaft to complete one revolution only, and means for preventing said operating device from shifting during the revolution of said main shaft. 110

2. In a cash controlling apparatus, the combination with an electromotor, of a frame, a main shaft in said frame adapted to be driven from said electromotor, a cut-out, a circuit including said electromotor and said cut-out, a cash receiving device, a cash registering device, two pinions loose on said main shaft and adapted to drive separately said receiving device and said registering 125 device. 130

device, two clutches longitudinally movable on said main shaft, a shifter guided in said frame and adapted to simultaneously operate said two clutches, said two clutches being 5 adapted to engage said two pinions simultaneously for the middle position of said shifter and one of them only for either extreme position, a lever adapted to close said cut-out, a key-operated mechanism adapted 10 to depress said lever, a rod longitudinally guided in said frame and adapted to depress said lever, a pin on said frame, a hand-lever rocking on said pin and adapted to shift said shifter, and a second hand-lever rocking on 15 said pin and adapted to depress said rod in either extreme position.

3. In a cash controlling apparatus, the combination with a frame, of a main shaft in said frame, means for driving said main shaft, a cash receiving device, a cash registering device, two pinions loose on said main shaft and adapted to drive separately said receiving device and said registering device, two clutches longitudinally movable 20 on said main shaft, a shifter guided in said frame and adapted to simultaneously operate said two clutches, said two clutches being adapted to engage said two pinions simultaneously for the middle position of said 25 shifter and one of them only for either extreme position, a circuit including a cut-out, a lever adapted to close said cut-out, a key-operated mechanism adapted to depress said lever, a rod longitudinally guided in said 30 frame and adapted to depress said lever, a pin on said frame, a hand-lever rocking on said pin and adapted to shift said shifter, a second hand-lever rocking on said pin and adapted to depress said rod in either extreme position, said shifter having 35 tooth spaces, and a lock rocking on said frame and adapted to be normally held in one position by the pin of the other member of said friction clutch and on being released to engage in any tooth space of said 40 shifter for locking the latter.

5. In a cash controlling apparatus, the combination with a frame, of a cash transporting band, a shaft in said frame adapted to drive said cash transporting band, a cam disk on said shaft having several cams and spaces, a counting board mounted in said frame to rock, a rod pivotally connected at one end with said counting board and forked at the other end to be guided by said 45 shaft, and a roller on said rod adapted to roll on the periphery of said cam disk for rocking said counting board and to engage in any space of said disk for supporting said board.

ARMAND GODEFROID.
